UNITED STATES PATENT OFFICE.

LLOYD D. FREELAND, OF HALBRITE, SASKATCHEWAN, CANADA, ASSIGNOR TO
WILLIAM J. H. STRONG, OF CHICAGO, ILLINOIS.

HOT-AIR MOTOR.

1,342,501.

Specification of Letters Patent. Patented June 8, 1920.

Original application filed March 27, 1915, Serial No. 17,568. Divided and this application filed January 17, 1918. Serial No. 212,212.

To all whom it may concern:

Be it known that I, LLOYD D. FREELAND, a citizen of the United States, residing at Halbrite, Saskatchewan, Dominion of Canada, have invented a certain new, useful, and Improved Hot-Air Motor; and I do hereby declare the following to be a full, clear, and exact description of the invention, such as will enable others skilled in the art 10 to which it appertains to make and use the same.

My invention relates to improvements in hot air motors and has special reference to improvements in fuel fonts for such motors 15 and means for supporting the fonts in position.

This present invention was first disclosed in my co-pending application for patent on motor driven fans, filed March 27, 1915, 20 Serial No. 17,568, of which this application is a division.

The object of my invention is to provide simple and effective means for supporting the fuel font in position; to provide a font which can be readily and easily placed in position; to provide a font support which shall act automatically to receive and retain the font when the motor base is placed thereon, and to provide simple means for 25 releasing the font from the motor base.

My invention consists in the several features of construction and in the combinations and arrangements of devices and parts by which I am enabled to attain the above 30 mentioned and other objects and all as hereinafter described and particularly pointed out in the appended claims.

My invention will be more readily understood by reference to the accompanying 40 drawings forming part of this specification, and in which:

Figure 1 is a side elevation of a hot air motor having a base and fuel font constructed in accordance with my invention; 45 Fig. 2 is a bottom plan view of the motor;

Fig. 3 is a horizontal plan section on the line 3—3 of Fig. 1; and

Fig. 4 is a fragmentary vertical substantially central section on the line 4—4 of Fig. 2.

My improved hot air motor comprises a base 1 upon which the cylinder 2 is secured and supported. Upon the upper end of the

cylinder is secured and supported the crank 55 shaft housing 3.

Within the upper part 4 of the base 1 a thin walled cylinder 5 depends, which is incased by a guard 6, having a central opening 7 in its lower end. The upper end 4 60 of the base is provided with ventilating slots 8.

The lower part 9 of the base 1 is flared out to provide ample space to receive the fuel font 10, which is provided with a centrally located burner 11 adapted to project through the opening 7 and to heat the lower end of the depending cylinder 5.

The font 10 is relatively shallow and relatively large in diameter and is adapted to 70 be placed within the base from below. I provide stop shoulders 12, preferably three thereof, uniformly spaced and adapted to contact with the upper surface of the font to position the same within the base. 75

For holding the font in place against the stop shoulders 12, I provide two thin bent arms 13 which are curved horizontally to fit within the outer part of the base and below a horizontal circumferential shoulder 80 12', and are pivotally mounted at one end on the base. The opposite ends 14 of the arms are bent or formed upwardly to provide finger pieces 15 adapted to project upwardly through the openings 16 in the base. 85

To pivotally mount the arms 13 on the base I provide each thereof with a hole 17 adapted to receive a downwardly extending projection 18 secured upon the shoulder 12' of the base. These projections 18 are spread 90 apart sufficiently to give space to insert a screw or bolt 19 in the base between them by which screw I secure a crescent shaped guard 20 rigidly in place.

This guard member is also formed on a 95 curve, and its free ends extend around the base in opposite directions and serve to support the curved members 13 and to guide them in combination with the shoulder 12'. The free ends 14 of the members 13 overlap 100 each other as best shown in Fig. 2 so that when the finger pieces 15 are pressed toward each other the members 13 will be separated. These members are normally held at the inner limit of their movement 105 by means of a tension spring 21, which has its ends secured to the two ends 14, respectively, of the members 13.

I make the periphery of the fuel tank with a lower inwardly inclined circumferential shoulder 22 which is adapted to be engaged by the members 13 and by reason 5 of their being pressed toward each other by the spring 21 to hold the tank pressed against the shoulders 12.

- For the purpose of easily entering the font into the position within the arms 13, 10 I make the upper part 23 of the periphery of the font inwardly inclined or cone shaped, as shown, making the upper diameter small enough to be received within the members 13 when they are at their inner 15 positions and adapted to cause the members 13 to spread as the font is pressed upwardly into the base or the base is forced downwardly upon the font.

The construction of the font and the font 20 holding arms 13 is such that the font can readily be entered into the base from below by merely placing the motor down over and upon the font.

The weight of the motor is sufficient to 25 cause the arms 13 to be spread as they slide down the upper coned or beveled periphery of the font and thus permit the entering of the font. Once the largest diameter of the font has passed the arms 13 the spring 30 21 acts to forcibly press the arms toward each other and lift the font into contact with the stop shoulders 12 by reason of the beveled lower portion of the periphery of the font.

35 After the font has been thus placed in position, it is securely held in the base and is portable with the motor.

To release the font it is only necessary to lift the motor off, first separating the arms 40 13 by pressing the finger pieces 15 toward each other so that the arms 13 will pass the largest diameter of the font.

As many modifications of my invention 45 will readily suggest themselves to one skilled in the art, I do not limit or confine my invention to the specific structures herein shown and described.

I claim:

1. In a hot air motor, a chambered base 50 open at its lower end, a fuel font adapted to be received in said base through said open end, yielding means within the base for engaging the font to retain it in the base, and font release means accessible from the outside of the base.

2. In a hot air motor, a chambered base open at the bottom, a fuel font for placement within said base through said open bottom, arms within the base yieldingly held in font engaging position, and means projecting through the base for separating the arms to release the font.

3. In a hot air motor, a hollow base open 65 at its lower end for receiving a fuel font therethrough, a plurality of fuel font sup-

porting arms pivotally mounted within the base, and means yieldingly holding said arms toward each other for supporting a font.

4. In a hot air motor having a hollow 70 base open at its lower end and adapted to receive a fuel font, a pair of font supporting arms each pivotally mounted at one end on the base and movable toward and from each other to engage and disengage a fuel 75 font, and a spring yieldingly holding said arms in font supporting position.

5. In a hot air motor, a chambered base open at its lower end, a plurality of font supporting arms pivoted to said base, means 80 yieldingly holding said arms toward each other, a fuel font adapted to be received in said base, the upper portion of the periphery of the font being cone shaped or beveled to spread said arms apart when the font is 85 entered into the base.

6. In a hot air motor, a chambered base open at its lower end, a pair of font supporting arms pivoted to the base, means 90 yieldingly holding said arms toward each other, a fuel font adapted to be received in said base, the upper portion being beveled to spread said arms to permit the font to pass into the base, and the lower portion of the periphery of the font being beveled 95 to enable said arms to approach each other and thus lift the font.

7. In a hot air motor, a chambered base adapted to receive a fuel font, font supporting arms pivoted to said base, and 100 means accessible from the outside of the base for moving said arms.

8. In a hot air motor, a chambered base adapted to receive a fuel font, font supporting arms pivoted to said base, means 105 yieldingly holding said arms toward each other in font supporting relation, and means accessible from the outside of the base for spreading said arms to permit the removal of the font.

9. In a hot air motor, a chambered base adapted to receive a fuel font, arms arranged within the base adapted to surround and support a fuel font, the arms perforated at one end adapted to receive projections fixed upon the base for pivotally mounting the arms on the base, a guard fixed to the base and overlapping both of said arms for supporting said arms in font supporting position, and a spring yieldingly holding said arms toward each other to support a font.

10. In a hot air motor, a chambered base adapted to receive a fuel font, font supporting arms pivotally mounted at one end 125 upon the base, a spring adapted to hold the opposite ends of the arms toward each other for supporting a font, the free ends of the arms being arranged in overlapping condition and provided with portions adapted 130

to project through the base, said projecting portions being adapted to be moved toward each other against the action of said spring to release the font.

- 5 11. In a hot air motor, a chambered base, a plurality of arms pivoted to said base, means tending to move said arms toward each other for supporting a font, means accessible from the outside of the base for 10 separating said arms for removing a fuel font adapted to be received in said base,

the upper portion of the periphery of said font being beveled to spread said arms apart when the base is lowered upon the font, and stop means within said base above 15 the font, the lower portion of the periphery of said font being beveled to enable said arms to approach each other and thus lift said font into contact with said stop means.

In testimony whereof I have hereunto 20 signed my name.

LLOYD D. FREELAND.
